UNITED STATES PATENT OFFICE.

WERNER SCHÄFFER, OF LAUPEN, NEAR BERN, SWITZERLAND, ASSIGNOR TO CHOCOLAT TOBLER HOLDING CO., AKTIENGESELLSCHAFT, OF SCHAFFHAUSEN, SWITZERLAND, A FIRM.

LINE-PRINTING TYPEWRITER OR THE LIKE MACHINE.

Application filed May 4, 1926, Serial No. 106,668, and in Germany May 6, 1925.

This invention relates to a line-printing typewriter or the like machines with preparatory adjustment of the writing position of the type carriers and consists more particularly in the fact that the individual rows of abutments or stops for the preparatory adjustment of the writing position of the letters for the whole line or at least for rather large groups thereof are arranged on a common carrier (box, plate or the like) which is movable in the direction of the rows of abutments. The abutments are preferably constructed in the form of levers. The adjusted abutments may be adapted according to their position to take with them through different distances devices for lifting magazines or devices for determining the position of type bars in the writing position. This may be effected owing to the fact that the abutments engage stationary projections on these devices. Supplementary abutments capable of being engaged or disengaged by depressing the shift key may also be provided, the said supplementary abutments resulting in the adjusted abutments coming into action earlier or later. These supplementary abutments are preferably arranged on rockable levers, and the rockable levers, corresponding to one another, of the individual adjacent rows of abutments are preferably rotatably supported upon continuous shafts. The boxes or the like carrying the movable abutments are preferably horizontally displaceable. The normalizing or releasing of the adjusted abutments may be effected by means of a stationary device brought within reach of the adjusted abutments during the return movement of the box or the like carrying the abutments, into its position of rest. This device preferably consists of a cross-bar which participates in the movement of the box for the purpose of acting upon the devices for adjusting the type carriers into the writing position, and upon the return of the box into its original position, remains stationary until it has effected the releasing of all the adjusted abutments. The rockable shift levers are preferably so designed that they are rocked back into their normal position upon the adjustment being effected by means of the cross-bar or the like effecting the

general release. The movable abutments serving for moving the rockable shift levers are preferably guided back to their position of rest by means of a stationary abutment during the forward movement of the box or the like. The apparatus which brings the type bars or the magazines containing the type into the predetermined position for writing may consist of rods which are guided in rake-like members of the box or the like. The rods may comprise projections against which the box strikes during its return movement, so that it takes the bars with it in its further movement and thereby returns the moving device for the magazines and the type bars to the position of rest. The bars serving for lifting the magazines are preferably connected by a slot-guide with the levers that lift the magazines.

The invention is illustrated by way of example in the accompanying drawings where-

in:

Figure 1 shows a longitudinal section through a line-printing typewriter according to the invention in the position of rest,

Figure 2 a similar longitudinal section through the machine in a position in which the type bars are brought into the writing position,

Figure 3 a partial cross section on the line A—A in Figure 2 and

Figure 4 an enlarged side elevation of the shifting mechanism.

The keys 1 pivoted to the machine may act in a known manner upon bars 2 movable in their longitudinal direction in such a way that upon a key being depressed in the direction of the arrow *a* the bars 2 move from left to right in the direction of the arrow *b*. The movement of these bars may be effected by the keys either directly, as illustrated in the drawing, or indirectly, in a manner not illustrated, by means of eccentrics engageable by the keys and moved by means of continuously rotating rollers. Each of the bars 2 connected each with one key is provided with teeth or projections 3 which can act in a known manner upon rockable bars 4 in such a way that the latter, during the movement of the bars in the direction of the arrow *b* are rocked by a definite amount. The rocking

bars 4 act in a known manner upon the adjusting flaps or hammers 5 of an adjusting mechanism 6 travelling step by step transversely through the machine in the direction 5 of the arrow *c* (Fig. 3). 7, 7 are bars slidable in their longitudinal direction, which at one end receive in a slot 25 a transverse pin 26 of a bell-crank lever 8 rotatably supported upon a stationary shaft. The arm of the 10 bell-crank lever 8 which is not connected with the bar 7 acts upon the bottom member of a magazine 9 in which a series of type bars 11 are arranged, lying one above the other. 10, 15 10 are bars or pushers, slidable in their longitudinal direction and having a U-shaped bend at one end, which are adapted to move the type bars which lie in front of the ends of their upper parts, out of the magazines and between the blades 12 of a mechanism 13 which in a known manner serves for justifying the line formed by the adjusted type bars. 20 14 is a table-plate upon which the type bars 11 rest in the justifying mechanism 13, while 15, 15 are mechanisms which are pressed downwards on to the type bars, engage in notches 25 on the upper side of the type bars, and thereby bring about an alignment of the type bars. The line of printing formed by the type bars is caused, after being inked, to produce an 30 impression in a manner known in itself by depressing the platen 16. The adjusting hammers 5 co-operate with adjustable projections, such for example as bell-crank levers 21, 31 which are carried by boxes or frames 20, 30. 35 The abutments 21, 31 are arranged in a plurality of adjacent rows which consist of a number of abutments located one behind the other, upon stationary transverse shafts 29 carried by the boxes 20, 30. The number of 40 adjacent rows of these abutments corresponds to the maximum possible number of characters of the widest line capable of being produced by means of the machine.

The method of working of the machine up 45 to this point is as follows:—Upon a key 1 being depressed the bar 2 connected with it is moved in the direction of the arrow *b*. The projections 3 on this bar each act upon a definite rocking bar 4, which in its turn rocks a definite adjusting hammer 5 of the adjusting 50 mechanism 6 in such a way that the adjustable projection or bell-crank lever 21 of the upper case or box 20, or 31 of the lower case 30, standing just opposite to the said adjusting hammer 5 is adjusted in such a way that it projects with one of its limbs beyond the upper or lower edge of its case. Each bar 2 is in contact by one of its ends with a rocking bar 41, so that the latter is rocked each time 55 a key is struck. This rocking bar 41 brings about in a known manner the feeding forward of the adjusting mechanism 6 in such a manner that the latter (like the paper carriages in the case of ordinary typewriting machines) 60 upon the key being released, is fed forward 65

an amount corresponding to one tooth on a rack, so that it can now act with its adjusting hammers upon the adjacent row of projections 21, 31. In this manner for each character of the line to be written, a definite projection 31 70 and 21 is adjusted. After the adjustment for the whole line is terminated and the adjusting mechanism has reached the end of its path the cases 20 and 30 are moved in the direction of the arrows *e*. Under these circumstances the adjusted projections 21 and 31 engage corresponding projections 22 and 32 on the bars 7 and 10 respectively and take these with them up to the end of their movement. The upper case 20 is moved first and by the 80 movement of the bars 7 and bell-crank levers 8 a lifting of the individual magazines up to a predetermined height is effected. All the adjusted projections of the box 20 follow the same path, while the bars 7, according to which bell-crank lever 21 is adjusted, are carried along a different distance. In the movement of the lower case 30 the push bars 10 are taken with them in a similar manner, by the 85 adjusted abutments 31, through different distances in the direction of the arrow *d* and these push bars move the type bars lying in front of them out of the magazines, as mentioned above.

The restoring of the adjusted projections 90 21 and 31, that is to say the returning of these projections into their positions of rest, is effected in a simple manner by cross-bars 28 and 38 respectively, which participate in the motion of the boxes or frames 20 and 30 respectively in the direction of the arrow *e*, but in the case of the direction of this movement being reversed, they are held fast in a convenient manner until all the rows of projections have travelled past below or above them. Upon striking against this bar the adjusted projections 21 or 31 are returned of themselves to their positions of rest. After the releasing is completed the bars 28 and 38 are automatically brought back into 100 their positions of rest. The returning of the parts that move the magazines, that is, of the bars 7 and of the push bars 10 that move the type bars out of the magazines, is effected in a simple manner by stationary projections 105 27 and 37 respectively on the said parts, which are carried along by the rear walls of the boxes 20 and 30 during their return movement. The bars 7 are supported in the rack-like or comb-like walls 23 and 24, Fig. 2, of 110 the upper case 20, so that an accurate meeting of the adjusted projections and of the stationary projections of these bars is ensured. The ends of the bars 7 might also be pivotally connected with the bell-crank levers 8 that 115 lift the magazines in a manner different from the manner illustrated in the drawing.

The movement of the cross bars 28 and 38 may be effected, for example, by an arrangement such as shown in the Patent No. 120

- 1,669,932. According to the disclosures of this application the cases 20 and 30 may be moved to-and-fro as above described, for instance by rods actuated by a cam wheel on a shaft, and the cross bars 28 and 38 may be moved to-and-fro, for instance, by other rods actuated by a cam wheel on the same shaft. Thus the movement of the cross bars is dependent on the movement of the cases 10 and can be made without difficulty (for instance by a respective forming of the cam wheels) in such a manner that when the cam wheels are rotated, the cross bars are moved together with the cases in the forward movement of the cases, (arrow *e*) and then held fast during the backward movement of the cases, and then moved back after the backward movement of the cases has ended, as above described.
- 20 The shifting, which renders it possible that according to the wish of the operator, upon a key being struck, one of two characters marked thereon is actuated, is not brought about according to the present invention by 25 two parts being moved relatively to one another but by the fact that the stationary projections, which are arranged on the devices 7 lifting the magazines and on the push bars 10, are widened upon the shift key being depressed. By this means the result is obtained that upon the cases 20 and 30 being moved the adjusted projections engage the said devices 7 and 10 earlier, and therefore take them a greater distance, than would occur without depression of the key. The widening of the projections 22 and 32 is effected in a simple manner owing to the fact that a tooth 35 which is preferably arranged on a rockable double lever 34, upon 30 the shift key being depressed, is brought in front of the stationary projection 22 or 32 and between the latter and the adjustable projections 21 and 31 respectively. The so-called shift key is one of the keys 1 of the key-board, and similar to the other keys 1 of the key-board. The shift key is connected in the same manner as the other keys 1 to a bar 2. The bar 2, to which the shift key is connected, is provided with a projection 3^a (Fig. 1) and upon the shift key being depressed the rod 2 having a projection 3^a is moved in the direction of the arrow *b* and with its projection 3^a moves rocking bars 4, which by means of special adjusting hammers 5 of the device 6 travelling through the machine, adjust projections 21^a and 31^a respectively. These projections are longer than the others and serve merely for the adjusting of the shift levers 34 in that during 40 the movement of the boxes 20 and 30 in the direction of the arrows *e* they strike against the hook-shaped ends of the shift levers and rock the latter, in which case, after the rocking of the levers, they can pass over them. 45 The rocking is such that the teeth 35 of the
- shifting levers, as shown on an enlarged scale in Figure 4, are brought out of the position in which they lie out of reach of the adjustable projections 21 and 31 into a position in which they place themselves in front of the projection 22 of the appropriate bar 7 or push bar 10 and come within reach of the adjustable projections. The releasing of the shift lever is effected owing to the fact that the bent tail-like part of all the adjusted shift levers 34 runs up on the above-mentioned cross-bars 28 or 38 which are carried along in the movement of the boxes 20 and 30 in the direction of the arrow *e*, and are held fast until the abutments 21, 31 are restored 50 so that the adjusted levers are rocked back into their original positions. The restoring of the adjustable projections 21^a and 31^a which act upon the shift levers, is effected by a stationary abutment, a stationary bar 55 36 for example, against which the ends of the said adjusted projections strike at the end of the movement of the boxes 20 and 30 in the direction of the arrow *e*. The holding of the shift levers and of the adjustable projections 21 and 31 in the position of rest or in the adjusted position may be brought about by any suitable means, as for example by plate-shaped clamping springs arranged 60 on the rotating shafts.
- I claim:—
1. In a machine of the character described, a plurality of rows of abutments arranged substantially parallel to each other, a key-board for selecting an abutment in each said rows according to the depression of the keys of the said key-board, a common carrier for said rows, movable in the direction of a row and a plurality of members each adapted to be engaged by a selected abutment. 100
  2. In a machine of the character described, a plurality of rows of abutments arranged substantially parallel to each other, a key-board for selecting an abutment in each row according to the depression of the keys of the said key-board, a common carrier for the said rows, movable in the direction of a row, a plurality of movable magazines, a series of type carriers in each said magazine, and a plurality of movable means corresponding to the rows and each adapted to be engaged by a selected abutment and when engaged to move a magazine corresponding to the situation of the respective selected abutment. 110
  3. In a machine of the character described, a plurality of rows of abutments arranged substantially parallel to each other, a key-board for selecting an abutment in each said rows according to the depression of the keys of the said key-board, a common carrier for the said rows, movable in the direction of a row, a plurality of type-bars each with a series of types, and a plurality of movable means corresponding to the rows and each adapted to be engaged to move a said type. 120
  4. In a machine of the character described, a plurality of rows of abutments arranged substantially parallel to each other, a key-board for selecting an abutment in each said rows according to the depression of the keys of the said key-board, a common carrier for the said rows, movable in the direction of a row, a plurality of type-bars each with a series of types, and a plurality of movable means corresponding to the rows and each adapted to be engaged to move a said type. 125
  5. In a machine of the character described, a plurality of rows of abutments arranged substantially parallel to each other, a key-board for selecting an abutment in each said rows according to the depression of the keys of the said key-board, a common carrier for the said rows, movable in the direction of a row, a plurality of type-bars each with a series of types, and a plurality of movable means corresponding to the rows and each adapted to be engaged to move a said type. 130

- bar corresponding to the situation of the respective selected abutment.
4. In a machine as claimed in claim 1, the said abutments being in the form of rockable levers.
5. In a machine as claimed in claim 1, the said abutments being in the form of rockable levers, a rockable lever of each of the said rows being arranged on a common axle.
- 10 6. In a machine of the character described, a plurality of rows of abutments, a key-board for selecting an abutment in each row, a member for each row provided with engaging means to be engaged by a selected abutment of a row, in combination with changing means for changing the moment in which the said selected abutment engages the engaging means.
7. In a machine of the character described, 20 a plurality of rows of selectable abutments, a keyboard for selecting an abutment in each said row, a shift key in the said keyboard, a plurality of members each provided with a projection adapted to be engaged by a selected abutment of a said row, when the shift key is not depressed, a rockable lever on each member and a projection on each said lever adapted to be engaged by a selected abutment of a row when the shift key is depressed.
- 25 8. In a machine of the character described, a plurality of rows of abutments arranged substantially parallel to each other, a key-board for selecting an abutment in each row according to the depression of the keys thereof, a plurality of carriers each adapted to carry a plurality of said rows, and to be moved in the direction of a row and a plurality of members each arranged to be engaged by a selected abutment.
- 30 9. In a machine of the character described, a plurality of rows of abutments arranged substantially parallel to each other, a key-board for selecting an abutment in each row according to the depression of the keys thereof, a plurality of carriers each adapted to carry a plurality of said rows, and to be moved in the direction of a row, a plurality of members each arranged to be engaged by a selected abutment, a carriage stepped 45 through the machine according to the striking of the keys, one of said carriers being arranged above the said carriage and another carrier being arranged below the said carriage.
- 50 10. In a machine of the character described, a plurality of rows of abutments arranged substantially parallel to each other, a key-board for selecting an abutment in each row according to the depression of the keys thereof, a plurality of carriers each adapted to carry a plurality of said rows, and to be moved in the direction of a row, a plurality of members each arranged to be engaged by a selected abutment, a carriage stepped 55 through the machine according to the striking of the keys, one of said carriers being arranged above the said carriage and another carrier being arranged below the said carriage.

the striking of the keys, one of said carriers being arranged above the said carriage and another carrier being arranged below the said carriage, and a carrier immediately adjacent to said carriage.

70 11. In a machine of the character described, a plurality of rows of selectable abutments, a key-board for selecting an abutment of any row, a shift key in said key-board, members each provided with a projection to be engaged by a selected abutment of a row, a rockable lever on each member and a projection on each lever for engagement with a selected abutment of a row when the shift key is depressed, the projections of the rockable levers 75 constructed to form extensions of the respective projections of the members.

12. In a machine of the character described, a plurality of rows of abutments, a keyboard for selecting an abutment in each row, a member for each row provided with engaging means to be engaged by a selected abutment of a row, in combination with changing means for changing the moment in which the said selected abutment engages the engaging means, and means for automatically restoring the changing means.

80 13. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, said changing means comprising a double-armed, releasable lever having an abutment, and a movable rod crossing the machine for restoring said lever to 85 normal position.

90 14. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, said changing means comprising a double-armed, releasable lever having an abutment, and a movable rod crossing the machine for restoring said lever to 95 normal position, there being one such lever on each member.

100 15. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means and comprising a double-105 armed rockable lever provided with an abutment and arranged on each member, and a 110

105

110

115

125

130

movable rod crossing the machine for restoring a plurality of said rockable levers.

16. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, the said rows being arranged substantially parallel and simultaneously movable in the direction of a row, each selected abutment during its movement taking with it a member.

17. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, consisting of a lever provided with an abutment, a shift-key in the keyboard, a second lever in each row of abutments for transmitting the movement of the shift-key to the changing lever, and means for restoring said second lever into its normal position.

18. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, consisting of a lever provided with an abutment, a shift-key in the keyboard, a second lever in each row of abutments for transmitting the movement of the shift-key to the changing lever, and means for restoring said second lever into its normal position, said restoring means consisting of a rod crossing the machine and remaining at rest during the movement of said rows.

19. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, said changing means consisting of a lever provided with an abutment, a shift-key in the keyboard, a second lever in each row of abutments for transmitting the movement of the shift-key to the changing lever, and a bar crossing the machine for restoring the second levers and remaining at rest while moving said rows.

20. In a machine of the character described, a plurality of rows of abutments, a

keyboard for selecting an abutment in each row, a member for each row provided with engaging means to be engaged by a selected abutment of a row; in combination with changing means for changing the moment in which the said selected abutment engages the engaging means, the said rows being arranged substantially parallel to each other and adapted to be moved simultaneously in the direction of a row, and the selected abutments being each adapted while being moved to take with them a member, and restoring means for restoring the selected abutments.

21. In a machine of the character described, a plurality of rows of abutments, a keyboard for selecting an abutment in each row, a member for each row provided with engaging means to be engaged by a selected abutment of a row; in combination with changing means for changing the moment in which the said selected abutment engages the engaging means, said rows being arranged substantially parallel to each other and adapted to be moved simultaneously in the direction of a said row, the selected abutments being each adapted while being moved to take with them a member, restoring means for restoring the said selected abutments, the said restoring means connected to a bar crossing the machine and adapted to be moved in the direction of a row.

22. In a machine of the character described, rows of abutments arranged substantially parallel to each other and adapted to be moved simultaneously in the direction of a said row, a member for each row of abutments, the said selected abutments being each adapted while being moved to take with them a member, restoring means for restoring the selected abutments, said restoring means consisting of a bar crossing the machine and adapted to be moved in the direction of a row, and rockable levers also restored by said bar.

23. In a machine of the character described, rows of abutments arranged substantially parallel to each other and adapted to be moved simultaneously in the direction of a row, a member for each row of abutments, a carrier for a series of rows, said selected abutments being each adapted while being moved to take with them a member, restoring means for restoring the said selected abutments, the said restoring means connecting in a bar crossing the machine and adapted to be moved in the direction of a row, said bar being adapted after being moved to remain at rest while the said row carriers are moved back.

24. In a machine of the character described, rows of abutments arranged substantially parallel to each other and adapted to be moved simultaneously in the direction of a row, a member for each row of abutments, carriers for series of rows of members, the

selected abutments being each adapted while being moved to take with them a member, restoring means for restoring selected abutments, the said restoring means connecting in a bar crossing the machine and adapted to be moved in the direction of a row, said bar being adapted after being moved to remain at rest while the row carriers are moved back, and to be moved forward together with the said row carriers and back after having restored the selected abutments.

25. In a machine of the character described, a plurality of movable magazines each having a series of type-carriers, means for moving the said magazines and comprising longitudinally movable rods, means for moving each rod in the direction of its longitudinal axis, and openings in the casing of the machine for guiding and spacing said rods.

26. In a machine of the character described, a keyboard, a row of abutments each adapted to be selected and shifted on the striking of a key of the said keyboard, the said row being movable in the direction of the said abutments, and a member adapted to be engaged and moved by a said shifted abutment.

27. In a machine of the character described, a keyboard, a row of abutments each adapted to be selected and shifted on the striking of a key of the said keyboard, the said row being movable in the direction of the said abutments, and a member adapted to be engaged and moved by a said shifted abutment, a shiftable changing means on said member for changing the movement in which the said shifted abutment engages the said member.

28. In a machine of the character described, a keyboard, a row of abutments each adapted to be selected and shifted on the striking of a key of the said keyboard, the said row being movable in the direction of the said abutments, and a member adapted to be engaged and moved by a said shifted abutment, and a magazine with a plurality of type bars, said member being adapted to move the said magazine.

29. In a machine of the character described, a keyboard, a row of abutments each adapted to be selected and shifted on the striking of a key of the said key-board, the said row being movable in the direction of the said abutments, and a member adapted to be engaged and moved by a said shifted abutment, and a magazine having a plurality of type bars, said member being adapted to move a type bar out of the said magazine.

30. In a machine of the character described, a keyboard, a plurality of rows of abutments, each of said abutments being adapted to be selected and shifted on the striking of a key

of the keyboard, the said rows being movable in the direction of said abutments, and a plurality of members for moving types each adapted to be engaged and moved by a shifted abutment.

31. In a machine of the character described, a keyboard, a plurality of rows of abutments, each of said abutments being adapted to be selected and shifted on the striking of a key of the keyboard, the said rows being movable in the direction of the said abutments, and a magazine having a plurality of type bars and a member for moving said magazine, and another member to move a type bar out of the said magazine, each of said members being adapted to be engaged and moved by a shifted abutment.

32. In a machine of the character described, a keyboard, a plurality of rows of abutments, each of said abutments being adapted to be selected and shifted on the striking of a key of the keyboard the said rows being movable in the direction of the said abutments, a plurality of magazines each having a plurality of type bars and a set of members being adapted to move the magazines and another set of members being adapted to move a type bar out of each of the said magazines, each of said members being adapted to be engaged and moved by a shifted abutment.

33. In a machine of the character described, a plurality of rows of abutments arranged substantially parallel to each other, a keyboard, and means to be moved by the keyboard and to select thereby an abutment, said means upon successive depressions of a key being arranged to select an abutment of an other row of abutments.

34. In a machine of the character described, a plurality of rows of abutments, a keyboard for selecting an abutment in each row, and a member for each row provided with engaging means to be engaged by a selected abutment of a row; in combination with changing means for changing the moment in which the said selected abutment engages the engaging means, said changing means consisting in an abutment which is adapted to be shifted by depressing a shift key of the said key board.

35. In a machine of the character described, a plurality of rows of abutments, a keyboard for selecting an abutment in each row, and a member for each row provided with engaging means to be engaged by a selected abutment of a row; in combination with changing means for changing the moment in which the said selected abutment engages the engaging means, said changing means consisting in a changing lever provided with an abutment.

In testimony whereof I affix my signature.

WERNER SCHÄFFER.
